Application filed August 26, 1931. Serial No. 559,557.

This invention relates to dispensing caps
for bottles and especially for containers for
mucilage although it will be quite obvious
that the principle involved adapts the
5 invention equally well to the dispensing of
other materials.

The primary object of the invention con-
sists in the provision of a cap of rubber or
the like of the type which employs a self-
10 closing slit and resides in modifying prior
constructions so that pressure of the cap on
the paper or other surface to be supplied
with mucilage automatically increases the
15 pressure within the container and forces the
material outwardly through the dispensing
slit.

Other objects and advantages of the in-
vention will be apparent from the following
20 description when taken in connection with
the accompanying drawing, in which,

Figure 1 is a perspective view of the com-
plete device.

Figure 2 is a vertical sectional view of the
package, the lower part of the bottle being
25 shown in side elevation.

Figure 3 is a view of the device in dis-
pensing position, parts being shown in sec-
tion.

Figure 4 is a fragmentary view of the
30 device showing an extreme position of the
dispensing head in operation, and

Figure 5 is an end view of the device as
shown in Figure 4 looking in the direction
of the arrows 5-5.

35 Referring to the drawing in more detail
the numeral 1 indicates a container for the
mucilage, here represented as a bottle al-
though other types of containers are equally
well adapted to the invention.

40 The cap or closure for the bottle is pref-
erably made of rubber and is provided with
a neck engaging portion 2, formed of rela-
tively heavy material and adapted to lock
under the annular shoulder 3 formed on
45 the exterior of the bottle neck. Extending
upwardly from the neck engaging portion 2
of the cap is a cylindrical portion 4 also of
rubber but having its walls made thin
enough to be comparatively soft and flexible.

50 The outer end of the cylindrical portion

55 Application filed August 26, 1931. Serial No. 559,557.

This invention relates to dispensing caps
for bottles and especially for containers for
mucilage although it will be quite obvious
that the principle involved adapts the
5 invention equally well to the dispensing of
other materials.

nating the hands of the operator is entirely eliminated.

Having fully described the invention, what I claim as new and desire to secure by 5 Letters Patent is:

1. A rubber cap for dispensing mucilage or the like, comprising a portion adapted to surround and engage the neck of a bottle, a cylindrical portion of thin rubber communicating with said neck engaging portion but of substantially less diameter, said cylindrical portion including one relatively long vertical wall and a diametrically opposite and relatively short vertical wall, and a 10 flat, inclined wall connecting the upper ends of the long and short walls of the cylindrical portion and closing the outer end thereof, said inclined wall provided with a slit.

20

70 75 80 85

2. A rubber cap for dispensing mucilage or the like, comprising a portion adapted to surround and engage the neck of a bottle, a bulbous portion extending upwardly from the neck-engaging portion, a cylindrical portion of thin rubber communicating with and extending upwardly from the bulbous portion, said cylindrical portion including one relatively long vertical wall and a diametrically opposite and relatively short vertical wall, and a flat inclined wall connecting the upper ends of the long and short walls of the cylindrical portion and closing the outer end thereof, said inclined wall provided with a slit.
